UNITED STATES PATENT OFFICE.

WILLIAM W. WIGGS, OF CRAB ORCHARD, ILLINOIS, ASSIGNOR OF ONE-HALF TO WAYMAN L. WELBORN, OF CRAB ORCHARD, ILLINOIS.

WINDOW-SHADE.

1,084,051.

Specification of Letters Patent. Patented Jan. 13, 1914.

Application filed April 23, 1913. Serial No. 763,163.

To all whom it may concern:

Be it known that I, WILLIAM W. Wiggs, a citizen of the United States, residing at Crab Orchard, in the county of Williamson and State of Illinois, have invented certain new and useful Improvements in Window-Shades, of which the following is a specification, reference being had to the accompanying drawings.

10 This invention relates to window shades and has for an object to provide novel manually operated means which may be easily and conveniently manipulated to cause the spring roller to wind up the shade.

15 A further object is to provide an effective, neat and inconspicuous support for the spring roller and its controlling means.

A still further object is to provide a novel controlling lever and guard for the lever.

20 the guard preventing the operator's fingers from contacting with and soiling the shade.

With the above objects in view the invention consists of certain novel details of construction and combination of parts hereinafter fully described and claimed, it being understood that various modifications may be made in the minor details of construction within the scope of the appended claims.

30 In the accompanying drawings illustrating this invention:—Figure 1 is a front elevation showing the invention applied to a window. Fig. 2 is a plan view showing the spring roller and its supporting means with parts removed. Fig. 3 is a front elevation of the spring roller and its supporting means with parts broken away. Fig. 4 is a cross sectional view on the line 4—4 Fig. 2. Fig. 5 is a detail perspective view of the

40 guard.

Referring now to the drawings in which like characters of reference designate similar parts, 9 designates a window casing and 10 and 11 designate the upper and lower sashes respectively of the window.

The device comprising the subject-matter of this invention consists of a spring roller 12 which is journaled in angleiron brackets 13 and 14 that are secured to the ends of a

50 support in the nature of a slat 15. The journal 16 at one end of the roller is revolvably fitted in an opening 17 in the related angleiron bracket 13. The journal 18 at the opposite end of the roller is terminally flattened as shown at 19 and is fitted in a

slot 20 formed in the related angleiron bracket 14. The journal 18 is thus locked against turning and serves to wind up and hold one end of the helical controlling spring 21 of the roller, in the usual manner, when the shade 22 carried by the roller is pulled out.

A cap 23 is fitted on one end of the roller and is provided with an opening 24 which revolvably receives the journal 18. The cap is formed on the peripheral edge of its end face with a circular series of axially extending teeth 25, the purpose of which will presently appear.

A link 26 is slidably fitted in a longitudinal groove 27 formed in the top face of the slat 15, the outer end of the link being bent abruptly at a rightangle to produce a catch 28 that is adapted to engage with the teeth 25, the link being bent outwardly beyond the catch to produce a guide 29 which is slidably fitted in a guide opening 30 formed in the adjacent angleiron bracket 14.

For actuating the link a lever 31 is mounted in a recess 32 formed in the slat 15, the lever having an eye 33 intermediate its ends which interlocks with a hook 34 that is formed on the adjacent inner end of the link 26. The lever is equipped at the inner end with a coil spring 35 which is terminally connected to a stationary pin 36 disposed in the recess, this spring serving to hold the lever pressed against the adjacent wall of the recess in normal position, in which position of the lever the catch 28 is engaged with the teeth 25.

A finger rest 37 is fixed at the inner end in a recess 32, both the finger rest and the lever 31 extending forwardly beyond the front longitudinal edge of the slat and being curved in opposite directions. The finger rest forms an abutment against which the operator's forefinger may be placed while the operator's thumb is placed against the lever to exert pressure on the latter and move the latter toward the finger rest, during which movement of the lever the catch 28 is moved outwardly from engagement with the teeth 25.

A cover plate 38 is disposed on the slat 15 and forms a housing over the recess 32, the plate having at its forward edge an outwardly curved lip 39 which conforms to the contour of the spring roller and performs the function of a guard against which

the backs of the fingers of the operator's hand may bear while the lever is being manipulated, whereby soiling of the shade is prevented.

5. The shade is provided with eyes 40 which may be engaged with hooks 41 or the like disposed at or near the top of the window casing as shown in Fig. 1.

In operation, to draw down the shade the 10 lever 31 is pushed toward the finger-rest 37 and there held to release the catch 28 from the teeth 25, whereupon the curtain may be then pulled down to the desired extent. The lever is then released with a resultant engagement 15 of the catch with the teeth whereby the spring roller is held against rewinding the shade. To raise the shade the lever is pushed and held toward the finger rest with a resultant disengagement of the catch 20 from the teeth whereupon the spring roller is freed and is urged by its controlling spring to immediately wind the shade.

From the above description it will be seen that I have provided an extremely simple 25 and inexpensive device of the class described, wherein the manually controlled lever for operating the spring roller may be easily and conveniently manipulated, and furthermore that the device is neat and inconspicuous when applied, and still further that soiling of the shade by contact with the operator's hand is positively prevented.

What is claimed, is:—

1. A device of the character described including a support, brackets carried by the

support, a roller journaled in the brackets, such roller being provided with a series of notches in one of its ends, and an endwise movable member carried by the support and terminating in an angular portion adapted to be received in the notches of the roller whereby such roller may be held against rotation, the extremity of the angular portion of the endwise movable member being projected through one of the brackets whereby such member is maintained in operative relation.

2. A device of the character described including a support provided with a transverse recess and an elongated recess in communication with the transverse recess, brackets on the support, a roller journaled in the brackets, such roller having notches in one of its ends, an endwise movable member extending within the longitudinally directed recess and terminating in an angular portion adapted to be engaged with the notches of the roller, the extremities of such angular portion being directed through the adjacent bracket to maintain such member in operative position, and means for imparting endwise movement to the member mounted within the transverse recess of the support.

In testimony whereof I hereunto affix my signature in the presence of two witnesses.

WILLIAM W. WIGGS.
